UNITED STATES PATENT OFFICE.

GEORGE THOMPSON, OF SHELBY, OHIO, ASSIGNOR TO THE AUTOCALL COMPANY, OF SHELBY, OHIO, A CORPORATION OF OHIO.

ELECTRIC SIGNAL APPARATUS.

1,199,023.

Specification of Letters Patent. Patented Sept. 19, 1916.

Application filed June 22, 1914, Serial No. 346,427. Renewed July 28, 1916. Serial No. 111,960.

To all whom it may concern:

Be it known that I, GEORGE THOMPSON, a citizen of the United States, residing at Shelby, county of Richland, State of Ohio, have invented a certain new and useful Improvement in Electric Signal Apparatus, and declare the following to be a full, clear, and exact description of the same, such as will enable others skilled in the art to which it pertains to make and use the same, reference being had to the accompanying drawings, which form a part of this specification.

My invention relates to apparatus for ringing electric bells or sounding alarms at a plurality of distributed points and has for its object to produce an apparatus of this kind which shall be simple in construction; efficient and reliable in operation and shall possess great flexibility so as to make it easy to adjust it to produce any desired variety of signals.

The various features of novelty whereby my invention is characterized will herein-after be pointed out with particularity in the claims; but for a full understanding of my invention and of its object and advantages, reference may be had to the following detailed description taken in connection with the accompanying drawings, 30 wherein:

Figure 1 is a front elevation of the main controller or central station to which my invention particularly relates, illustrating one embodiment of my invention; Fig. 2 is a view partly in top plan and partly in section of the device shown in Fig. 1, on an enlarged scale; Fig. 3 is a section taken approximately on line 3—3 of Fig. 2; Fig. 4 is a transverse section on an enlarged scale 35 on line 4—4 of Fig. 2; Fig. 5 is a section through the rotatable contact arm, illustrating the manner in which it is mounted; Fig. 6 is a side elevation on an enlarged scale on the inner end of the stopping and starting plug; Fig. 7 is a section on line 45 7—7 of Fig. 6; Fig. 8 is a sectional detail illustrating the mounting for one of the stationary contact pieces; and Fig. 9 is a diagram of connections including four sectional views of the switch board.

My improved apparatus consists of two main groups of mechanisms, one constituting a contact maker including one or more rotatable contacts and any desired number of

stationary contacts, and the other consisting of a switch board suitably connected to the contact devices so that any desired alarm or signal may be produced by properly plugging in at the switch board. In the arrangement shown, the contact making devices and the switch board are mounted in close proximity to each other so as to be housed in a single casing; but it will of course be understood that this proximity of the two mechanisms or devices to each other is not essential. For the sake of brevity, I shall describe in detail, only the specific construction illustrated.

Referring to the drawings, 1 represents a shaft adapted to be driven by a suitable motor of any kind. In the arrangement shown, the motor, 2, is of the clockwork type having one or more winding stems, 3. Mounted upon the shaft so as to be rotatable therewith is a switch arm, 4. Mounted on a suitable supporting base, 5, below and in the plane of the switch arm is a metal plate, 6, having thereon a series of teeth, 7, arranged in the arc of a circle having its center at the axis of rotation of the switch arm. Adjacent to the end of the shaft 1 is a second plate, 8, arranged parallel with and at some distance away from the plate 6. The plates 6 and 8 are insulated from each other, this being conveniently accomplished by making the base member 5 on which they are mounted of insulating material. The plate 8, is provided with a metal bushing, 9, projecting laterally therefrom and surrounding the shaft 1. Within the bushing is a sleeve, 10, of insulating material which serves to insulate the shaft from the plate 8. The rotary switch arm, instead of being mounted directly on the shaft 1, is mounted upon the bushing 9 and has in one side thereof an insulated socket, 11, into which projects a pin or finger, 12, fixed to the shaft. With this arrangement, the switch arm is insulated from the shaft but is compelled to rotate positively with it. The plate 8 is provided with a series of stationary contact fingers, 13, which project therefrom into the spaces between the contact teeth of the plate 6 so as to form a series of stationary contacts situated in the same curved line as the teeth of the plate 6. The members 13 are preferably in the form of pins insulated from the plate 8. Thus, as illustrated in Fig. 8, each

of the pins may have a reduced screw threaded inner end, 14, which passes through a bushing, 15, set into the plate 8 and is provided with a nut, 16, engaging with an insulating washer, 17, to clamp the pin to the plate and at the same time insulate it therefrom. By elongating the reduced portion 14 and providing an additional nut, 18, means are provided for attaching a wire to the pin.

In the arrangement illustrated, the rotary contact arm is made double ended, each end being provided with a pivoted shoe, 20, normally yieldingly held by a spring, 21, so that its contact point or face is farther removed from the axis of rotation than the distance between this axis and the stationary contacts. Consequently, when the arm is revolved each of the pivoted contact pieces 20 is yieldingly pressed against the stationary contacts, one after the other. In the arrangement shown, the parts are so disposed that the stationary contacts form an arc of a circle somewhat less than 180 degrees 25 so that each of the pivoted contact pieces on the rotating arm will pass beyond the line of stationary contacts before the other begins to engage them.

Where the operating shaft is driven by a spring motor, the control of the rotary switch arm is through some means for normally restraining the motor and for releasing it as and when desired. In the arrangement shown, the movable arm 4 is provided with a circular hub, 23, having in the periphery a notch, 24. On the plate 8 is pivoted a dog, 25, having one end lying beneath the hub 23 and having at its other end a spring, 26, which tends constantly to press the dog against the periphery of the hub and cause it to drop into the notch 24 when the notch is in the proper angular position. The dog may be controlled in various ways. In the arrangement shown, there is a controlling bar, 28, projecting through the front of the inclosing casing, 29, and through a hole in the plate 8, this bar having a beveled inner end, 30, between which and the body of the bar is a groove for receiving the upper edge of the dog, 25. A portion of the groove, 31, is of such a depth that when the dog lies therein it occupies its locking position as illustrated in Fig. 3. Another portion, 32, of the groove is of such a depth that when the bar is turned so as to bring the upper edge of the dog into this portion of the groove, the dog is depressed so as to free it from the notch in the hub on the switch arm; thus releasing the motor and causing it to rotate the switch arm. The groove does not extend entirely around the locking bar so that when the bar is turned into the proper position it may be withdrawn bodily. After being withdrawn, it may be slipped 15 back in place and interlocked with the dog

by reason of its beveled end which allows it to ride upon the dog and depress the latter.

If the controlling bar is simply turned slightly from its normal position in which the locking dog holds the motor against operation and is then turned back again, time is given the motor in which to start and thus carry the notch in the hub on the switch arm through a sufficient angle to prevent it from being caught by the dog when the latter rises after having been momentarily depressed, and consequently the dog simply rides upon the periphery of the hub while the latter makes a complete revolution. As soon as a complete revolution has been made, 70 however, the dog drops into the notch and arrests the movement of the rotary arm. If, on the other hand, the bar 28 be turned so as to bring the dog into the portion 32 of the groove, and is left in this position, the 75 dog will be positively held away from the periphery of the hub on the switch arm and therefore the motor will continue to operate and this arm to rotate until the controlling bar is again shifted. In short, by a simple manipulation of the controlling bar the 80 motor may be caused to operate and to continue to operate until the switch arm has made a complete revolution; or, by a different simple manipulation of the controlling bar, the motor may be set in operation 85 and be allowed to continue to operate indefinitely.

The rotary switch arm is in electrical connection with the plate 8, while both the stationary contact fingers 13 and the contact plate 6 are insulated from the plate 8. Consequently by connecting the plate 8 to one side of a line containing a suitable source of electrical energy and a signaling device, 100 and connecting the stationary fingers and the plate 6 to the other side of the line, it will be seen that the gap between the two sides of the line will be bridged whenever one of the pivoted contact pieces on the 105 rotary arm engages with either a tooth on the plate 6 or with one of the stationary contact fingers. Furthermore, by leading the connections from the stationary contact fingers and from the plate 6 through a suitable switch board, any desired variety of 110 signals may be given.

In the arrangement illustrated, the plate 6 is utilized for the purpose of giving what may be termed a general signal or alarm, 115 such as a dismissal signal to notify the employees in a shop or factory that work is to cease, or for any other desired purpose; while the stationary contact fingers are adapted to give the special signals. I have 120 therefore run a single connection from the plate 6 and connections from each of the stationary contact fingers to a suitable switch board which may be located at any desired 125 point but which, in the arrangement illus-

trated, is located adjacent to the motor driven switch apparatus, heretofore described.

In the particular embodiment illustrated, 5 the switch board is set into the main casing and its front wall, 35, forms a portion of the front wall of the casing. A wire, 36, leading from the plate 6 is connected to the small contact plate or clip, 37, arranged on the rear side of the wall 35 in proximity to a plug-receiving hole, 38, in this wall.

39 is a suitable plug adapted to be inserted in the hole 38 and make electrical contact with the plate or clip 37; the plug being attached to a cable, 40, which constitutes one side of the line while a wire or cable, 41, attached to the plate 8 forms the other side of the line.

It will be seen that if the plug is inserted 20 in the hole 38 and the motor is set in operation, assuming that the wires or cables 40 and 41 are connected in a circuit containing a bell or other signal and a battery: The circuit through the bell or other signal will be 25 completed whenever one of the pivoted contact pieces 20 engages with one of the teeth on the plate 6; this circuit being from the wire 41, through the plate 8, through the rotary contact arm, through the plate 6, 30 through the wire 36 and clip 37 and thence to the plug 39 and cable 40.

The connections between the stationary contact fingers and the switch board are such that a great variety of signals may be given. 35 Thus if the signal is a bell, the bell may be caused to ring so as to sound any desired number of a series which represent different persons or things.

The details of the switch board are best 40 illustrated in Figs. 4 and 9. From Fig. 1 it will be seen that the front plate 35 of the switch board is provided with two rows of holes, 50 and 51, into any one of which holes the plug 39 may be inserted. In a suitable 45 box or casing, 52, of which the wall 35 forms the front cover, are arranged a series of long contact plates, lettered in the drawings *a* to *p* inclusive. The contact plates are at least as long as each of the rows of holes, 50 and 51, and they are arranged in groups of four, there being four plates above each row of holes and four plates below each row of holes. The plates of each group are spaced apart by strips of insulating material, 53. The end pieces, 54, of the box or casing are made of insulating material and have ledges or ribs, 55, projecting inwardly between the upper row of contact plates and the row just below the upper 55 row, and also between the lower row and the row just above the lower row. Each of the contact plates of the upper and the lower row is therefore arranged in a little compartment and this compartment has a vertical depth greater than the vertical

depth or width of the plate so as to allow the plate to move up and down a limited distance. Corresponding contact plates of the two intermediate rows occupy compartments in common with each other, these 70 compartments being also of such vertical depth that the plates are free to move up and down. Above each plate in the upper row is a light spring, 56; below each plate in the lowermost row is a similar spring, 57, 75 and between the corresponding plates in the intermediate rows are springs, 58; all the springs acting to press the two upper rows toward each other and to press the two lower rows toward each other. The edges 80 of the plates in proximity to the plug-receiving openings are notched according to any desired scheme, so that whenever the plug is inserted into one of the holes it will engage with any desired number of the adjacent eight contact plates and be out of engagement with the remainder; the springs acting to press those plates with which the plug engages yieldingly against the plug and thus secure a good electrical connection. 85

In the arrangement illustrated, one-half of the stationary contact fingers 13 are connected to the upper and lower rows of contact plates, each finger being connected to one of the plates in the upper row and to the 90 corresponding plate in the lowermost row. The other half of the contact fingers, alternating with those connected to the upper and lower rows, are connected to the intermediate rows of plates, each of these contacts being connected to one of the intermediate plates and through it to the one occupying the same chamber or compartment with it. The entire group of wires is indicated by the reference character, 60, 105 and, since the connections can readily be followed on Fig. 9 I shall not describe them in detail except to trace a single circuit.

Assuming that the wire 41 forms one end of a circuit containing a source of electrical energy, 61, and a signal, 62, and that the cable 40 and plug 39 form the other terminal of this circuit, assuming the switch plug to be placed in the right hand hole in the upper row of the switch board, looking at Fig. 9, and further assuming that the motor is running and is turning the switch arm 4: It will be seen that when the pivoted contact piece 20 on the rotating arm engages with the first or upper of the fingers 13, current will flow from the source of electrical energy through the rotary switch arm, the stationary contact finger, through the plate *a* in the switch board, through the plug 39 and back through the signal to the 110 source of electrical energy so that the signal will be sounded. The second contact finger from the top is connected to the contact plate *e* just below the plate *a*, and the plate *e* is provided with a notch which prevents it 115

from making electrical contact with the switch plug when the plug occupies the position specified. The plates *b* and *f* lie just behind the plates *a* and *e* and these are 5 notched so that although connected to the third and fourth fingers of the set 13, the circuit will not be completed when the rotary arm reaches them. The plates *c* and *g* lie just behind the plates *b* and *f* and they 10 are also notched so that although they are connected to the fifth and sixth fingers, the circuit will not be completed when the rotary switch member engages with these fingers. The plates *d* and *h* lie just behind 15 the plates *c* and *g*, these plates being connected to the seventh and eighth fingers. The plate *d* is notched so that when the rotary switch arm engages the seventh finger the circuit remains interrupted by the 20 switch board. The plate *h* is not notched in proximity to the first hole so that it engages with the switch plug and causes the circuit to be completed when the rotary switch arm contacts with the eighth finger. Consequently 25 the circuit will be completed twice by each end of the rotary switch arm during each complete revolution. A considerable interval elapses between successive closures of the circuit, so that if the signal 30 is a bell the effect will be of a single ring four times during each revolution or, in other words, number 1 will be called four times during each revolution. In the same way, if the plug be inserted in the second 35 hole from the right in the uppermost row in the switch board it will be seen that the bell will be sounded whenever the rotary switch member contacts with either of the first two fingers in the stationary set or with either 40 of the last two fingers. In other words, there will be two rings in quick succession, then a long interval, and then two more rings in quick succession. In the same way any number from three to eight may be 45 called by using the third to eighth holes of the upper row in the switch board. The remainder of the holes serve to produce signals corresponding to numbers of two or three digits.

50 It will thus be seen that I have produced a simple and compact controlling apparatus for an electric circuit by means of which a great variety of signals may be given or alarms sounded at any desired number of remote points, the signals or alarms being repeated a definite number of times and then ceasing or being repeated indefinitely until stopped by the operator.

55 While I have illustrated and described 60 with particularity only a single preferred form of my invention, I do not desire to be limited to the exact structural details thus illustrated and described; but intend to cover all forms and arrangements which 65 come within the terms employed in the defi-

nitions of my invention constituting the appended claims.

I claim:

1. In a device of the character described, a plate, a revoluble switch arm mounted on 70 said plate, a series of separated contacts arranged on said plate in an arc of a circle having its center at the axis of rotation of said arm, a motor for rotating said arm, a conductor, means for selectively connecting said contacts in various groups to said conductor, said arm having a contact piece lying at one side of the plane of the aforesaid plate, said contacts projecting laterally from the plate into said plane, and a metal 80 plate lying in said plane and having teeth projecting into the spaces between the aforesaid contacts but out of engagement therewith.

2. In a device of the character described, 85 a plate, a revoluble switch arm mounted on said plate, a series of separated insulated contacts arranged on said plate in an arc of a circle having its center at the axis of rotation of said arm, a motor for rotating said 90 arm, a conductor, means for selectively connecting said contacts in various groups to said conductor, a second series of electrically connected contacts arranged in said arc and alternating with the aforesaid contacts, and a piece on said switch arm for engaging with said contacts as the arm is rotated.

3. In a device of the character described, a plate, a series of insulated contact posts projecting laterally from one side of the 100 plate and arranged in an arc of a circle, a switch arm mounted on said plate so as to be revoluble about the center of said circle, a contact finger pivoted on said arm so as to be movable about an axis 105 parallel with the axis of rotation of the arm and located in position to engage successively with the sides of said posts as the arm is rotated, means for rotating said arm, a conductor, and means for selectively connecting said posts in various groups to said conductor.

4. In a device of the character described, 115 a casing, a switchboard arranged in the front wall of the casing, a supporting plate within the casing, a series of insulated contacts arranged on said plate in the arc of a circle, a switch arm revoluble about an axis passing through the center of said circle and adapted to engage with said contacts one 120 after the other as it revolves, a motor in said casing for actuating said arm, and connections between said contacts and said switchboard.

5. In a device of the character described, 125 a plate, a series of insulated contact posts projecting laterally from one side of the plate and arranged in the arc of a circle, a metal plate lying parallel with the aforesaid plate and having teeth projecting between 130

but out of engagement with said contacts, and a revoluble switch arm having its axis of rotation passing through the center of the aforesaid circle and having a part adapted 5 to engage with said contacts and said teeth as the arm is rotated.

6. In a device of the character described, a metal plate, a series of posts projecting laterally from one side of the plate in the 10 arc of a circle, insulation between each of said posts and the plate, a second metal plate arranged parallel with the aforesaid

plate and having teeth projecting between said posts and lying in the aforesaid arc, and a revoluble switch arm adapted to engage with said posts and said teeth successively. 15

In testimony whereof, I sign this specification in the presence of two witnesses.

GEORGE THOMPSON.
